UNITED STATES PATENT OFFICE.

JEAN E. SAUCIER, OF MONTREAL, QUEBEC, CANADA.

TROLLEY.

No. 877,953.

Specification of Letters Patent.

Patented Feb. 4, 1908.

Application filed October 6, 1905. Serial No. 281,578.

To all whom it may concern:

Be it known that I, JEAN E. SAUCIER, a subject of the King of England, residing at Montreal, Province of Quebec, Canada, have invented certain new and useful Improvements in Trolleys; and I do hereby declare that the following is a full, clear, and exact description of the invention, such as will enable others skilled in the art to which it appertains to make and use the same.

My invention relates to vehicles which derive their propelling power from a wire charged with electricity; the object of my invention is to provide means whereby 15 a constant current of electricity may be conducted from the wire to the car; a further object of my invention is to provide means to prevent breakage and wear of the wire caused by shocks received by the wire 20 from the member which makes the connection between the wire and the car; and my invention consists of the construction, combination and arrangement of parts as herein illustrated, described and claimed.

In the accompanying drawings forming 25 part of this application, I have illustrated one form of embodiment of my invention, in which drawings similar reference characters designate corresponding parts, and in 30 which:

Figure 1 is a side elevation of the upper end of a trolley pole and a portion of a trolley wire, showing the application of my invention; Fig. 2 is a plan view; Fig. 3 is an 35 enlarged plan of my invention detached; and Fig. 4 is a longitudinal vertical section through my invention detached.

Referring to the drawings, 5 designates an ordinary form of trolley pole, which is usually actuated upward by means of a spring, 40 and which is provided with an ordinary form of trolley wheel 6, adapted to bear against the wire 7. Disposed on the pole 5 adjacent its end is a yoke 8, provided with lugs 9 and 45 secured to the trolley pole 5 by means of the bolt 10.

Disposed between the arms of the yoke 8 is a yoke 11, pivotally secured to the arms of the yoke 8 by means of the rod 12. The 50 arms 13 of the yoke 11 are extended outward as at 14, and are curved with relation to the pole 5. Connecting the arms 13 at their outer ends, is a rod 15, on which is rotatably disposed a roller 16, preferably 55 convex in shape. The arms 13 of the yoke extend to a point adjacent the wheel 6, and

the roller 16 is adapted to bear at all times on the wire 7.

The arms 13 are provided with the integral lugs 17, adapted to prevent the wire 60 7 from passing between the wheels 6 and the arms 13 of the yoke. Connecting the arms 13 is a rod 18, to which is attached the trolley rope 19.

Connecting the arms 13 is a web 20, provided with a screw-threaded opening 21, in which is disposed a screw-threaded member 22, one end of which is adapted to bear against the under surface of the pole 5 and limit the movement of the yoke 11 towards 70 the wire 7, and by means of which the range of this movement may be adjusted.

Formed on the upper edge of the yoke 11, on both sides thereof, are integral lugs 23, supporting a pintle 24, which pintle carries 75 a spring 25.

Provided in the spring 25 is a screw-threaded opening 26, in which is disposed a bolt 27, and on the bolt is disposed an adjusting nut 28. The end of the spring 25 is 80 pivotally supported by the pintle 24, so that the spring is free to work upward and downward, and the nut 28 is adapted to contact against the under face of the spring, and the end of the bolt 27 is adapted to contact 85 against the under surface of the pole 5, the tension of the spring being adjusted by the bolt 30.

Connecting the arms 13 of the yoke adjacent its forward end, is a web 29, through 90 which is disposed a bolt 30, for adjusting the tension of the spring 25. The forward end of the spring 25 is curved, as at 31, and its extreme end is concaved, as at 32, to fit closely the under surface of the pole 5. 95

One important function of my improved device is the protection of the trolley wire from receiving the full force of the shock incident to placing the trolley wheel on the wire. Owing to the spring pressure on the 100 yoke 11, the roller 16 will normally rise somewhat above the wheel 6. Therefore, in placing the wheel on the wire, the first shock will be received by the roller 16, and mostly absorbed by the spring 25.

A further function of my device is to assist in maintaining a constant contact between the wheel and wire. By maintaining an additional spring pressed bearing point on the wire, the latter is steadied and prevented 110 in a great measure from rapid vibration, which is mainly responsible for the trolley

being thrown when the car is moving rapidly or is turning on curves or switches.

Having thus fully described my invention, what I claim as new and desire to secure by Letters Patent is:—

1. In combination with a trolley pole, a yoke secured thereon, a second yoke pivotally secured to the first yoke, a roller on the second yoke, a spring on the second yoke, and means for adjusting the tension of the spring.
  2. In combination with a trolley pole, a yoke secured thereon, and provided with integral lugs, a second yoke pivoted to the first yoke, a roller on the second yoke, a spring on the second yoke, and means for adjusting the tension of the spring.
  3. In combination with a trolley pole, a yoke secured thereon, and provided with integral lugs, a second yoke pivotally secured to the first yoke, and provided with curved arms, a roller on the second yoke, a spring on the second yoke, and means for adjusting the tension of the spring.
  4. In combination with a trolley pole, a yoke secured thereon, and provided with integral lugs, a second yoke pivotally secured to the first yoke, and provided with curved outwardly expanded arms, a roller on the second yoke, a spring on the second yoke, and means for adjusting the tension of the spring.
  5. In combination with a trolley pole, a yoke secured thereon, a second yoke pivotally secured to the first yoke, means for limiting the movement of the second yoke, a roller on the second yoke, a spring on the second yoke, and means for adjusting the tension of the spring.
  6. In combination with a trolley pole, a yoke secured thereon, a second yoke pivotally secured with the first yoke, and provided with a connecting web having a screw-threaded opening therein, a second threaded
- member disposed through the opening and adapted to contact against the pole, a roller upon the second yoke, a spring on the second yoke, and means for adjusting the tension of the spring.
7. In combination with a trolley pole, a yoke secured thereon, a second yoke pivotally secured to the first yoke, and provided with lugs thereon, a pintle disposed through the lugs, a roller on the second yoke, a spring disposed on the pintle, and means for adjusting the tension of the spring.
8. In combination with a trolley pole, a yoke pivotally secured therewith and provided with a web, a roller on the yoke, means for limiting the movement of the yoke, a spring pivotally secured to the yoke, and provided with a screw-threaded opening, a screw-threaded member disposed through the opening, and a screw-threaded member disposed through the web and adapted to contact against the spring.
9. In combination with a trolley pole, a member pivotally connected with the pole, a roller carried by said member, means for limiting the movement of said member, a curved spring pivotally secured to said member, and means for varying the tension of the spring.
10. In combination with a trolley pole, a member pivotally connected with the pole, a roller carried by said member, means for limiting the movement of said member, a curved spring pivotally secured to said member, and provided with a concaved end adapted to engage the trolley pole, and means for varying the tension of the spring.

In witness whereof I have hereunto set my hand in the presence of two witnesses.

JEAN E. SAUCIER.
